(57) **CLAIM**

The ornamental design for a tanning pool, as shown and described.

DESCRIPTION

FIG. 1 is a top, front, left side perspective view of a tanning pool, showing my new design;

FIG. 2 is a bottom, rear, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 in FIG. 1.

The unevenly dashed broken lines surrounding details shown in FIGS. 1 and 9 are for the purpose of annotating the enlarged views only and form no part of the claimed design.
